UNITED STATES PATENT OFFICE.

HENRY F. KELLNER, OF SILVER LAKE, KANSAS.

SILT-ACCUMULATOR.

1,389,513.

Specification of Letters Patent. Patented Aug. 30, 1921.

Application filed March 25, 1921. Serial No. 455,521.

To all whom it may concern:

Be it known that I, HENRY F. KELLNER, a citizen of the United States, residing at Silver Lake, in the county of Shawnee and State 5 of Kansas, have invented certain new and useful Improvements in Silt-Accumulators, of which the following is a specification.

This invention relates to an improvement in silt accumulators for use in forming deposits of silt in flowing waters and particularly for preventing erosion of the banks of streams, and has for one of its objects to provide such a form that the silt which moves near the bed of a stream may be accumulated 10 to advantage, the upper part of the accumulator having such form that its resistance to the force of moving water will not cause any material displacement of the device in the bed of the stream. The invention also 15 has for one of its objects to provide a silt accumulator consisting of few and simple parts so that it may be conveniently and economically constructed.

In the accompanying drawing, Figure 1 20 shows a perspective view of the silt accumulator in operative position. Fig. 2 is a view of the silt accumulator in side elevation. Fig. 3 is a top plan view of the same. Fig. 4 25 is a perspective view showing connected silt accumulators in a stream.

Referring now to the drawing, the silt accumulator α includes an approximately rectangular base consisting of elongated, horizontal, rigid members 5 connected at 30 their ends by bands 6 or other suitable means, together with horizontal, rigid members or cross-strips 7 disposed diagonally with reference to members 5, a rigid standard 8 being connected with the cross-strips 7 at their 35 intersection, a plurality of third rigid members or strips 9 being secured at their upper ends to the standard near the upper end thereof by bands 10, the lower ends of members 9 being secured by bands 6 to members 5 40 and 7 at or near the ends thereof.

As thus described an upright frame is provided of pyramidal form. Numerals 11 indicate strands which are connected at their upper ends with the standard, this connection 45 preferably being midway between the ends thereof, the lower ends of the strands 11 being secured to the ends of members 7 and 9 at the intersection thereof. Numerals 12 indicate secondary strands which are also 50 connected at their upper ends with the standard, midway between the ends of said stand-

ard, their lower ends being secured to the base of the silt accumulator, said connection being with the horizontal members 5, between the ends thereof or with the cross-strips outwardly from the band 13, the latter being used for securing the standard to the cross-strips at their intersecting parts.

In operation, for controlling or deflecting a current of water to cause precipitation of silt, a plurality of accumulators α are generally employed, their bases being connected by cables a and disposed near to each other, and connected with the shore by a cable b to partly obstruct a stream, anchors c being 60 used so that the bases will be maintained flatwise upon the bed of the stream. On account of the pyramidal form provided, together with the arrangement of the strands 65 11 and 12 which form a second permeable 70 frame of pyramidal form above the base having its apex terminating midway between the base and apex of the frame provided by the base and members 9, the water 75 will be deflected to advantage to cause accumulations 14 of silt in flowing water at the "down-stream" side of an accumulator. 80 However, since the upper part of the device will cause only a slight resistance, comparatively, to flowing water, overturning of the 85 accumulator is not likely to occur.

While I have described the construction in detail, I do not wish to be understood as limiting myself to exactness in this respect, and changes in form, size, proportion and 90 minor details may be made as found to be of advantage, the scope of the invention being determined by its claims.

I claim:

1. In a silt accumulator, a rectangular 95 base including rigid, elongated members connected at their ends and cross-strips disposed diagonally with reference to and connected with said rigid elongated members, a standard secured to the cross-strips at the 100 intersection parts thereof, rigid, elongated members connected at their lower ends with the base at the corners thereof and connected at their upper ends with the standard, and a plurality of strands connected with the 105 rigid, elongated members of the base and connected with the standard midway between the ends thereof.

2. In a silt accumulator, a rectangular 110 base including rigid, elongated members connected at their ends and rigid cross-strips disposed diagonally with reference to

and connected with said rigid, elongated members, a standard secured to the cross-strips at the intersecting parts thereof, rigid, elongated members connected at their lower ends with the base and secured at their upper ends to the standard, a plurality of strands connected at one of their ends with the rigid, elongated members of the base, and a plurality of second strands connected with the cross-strips, said first named strands and second strands being connected with the standard between the ends thereof.

3. In a silt accumulator, a base including rigid cross-strips having their intersecting parts connected, rigid supporting members connecting each terminal part of a cross-strip with the terminal part of an adjacent cross-strip, a rigid standard secured to the rigid cross-strips at the intersecting parts thereof, supporting-members connecting the standard near its upper terminal with the

end portions of the cross-strips and a plurality of strands connecting the standard, between its ends, with said base.

4. In a silt accumulator, a base including rigid cross-strips having connected intersecting parts, supporting-members connecting each terminal part of a cross-strip with the terminal part of an adjacent cross-strip, a standard secured to the cross-strips at the intersecting parts thereof, supporting-members connecting the standard near its upper terminal with the end portions of the cross-strips, and a plurality of strands connecting said base with the standard. 35

In testimony whereof, I have affixed my signature in presence of two witnesses.

HENRY F. KELLNER.
